DESIGN FOR A DISPLAY CASE

Anthony A. Rose, Oakland, Calif., assignor to Hamilton Display Case Mfg. Co. Inc., Los Angeles, Calif., a corporation of California

Application November 26, 1934, Serial No. 54,164

Term of patent 14 years

To all whom it may concern:

Be it known that I, Anthony A. Rose, a citizen of the United States, residing at Oakland, in the county of Alameda and State of California, have invented a new, original, and ornamental Design for a Display Case, of which the following is a specification, reference being had to the accompanying drawing, forming part thereof.

Figure 1 is a top plan view of the display case,
showing my new design;

Figure 2 is a front perspective view; and Figure 3 is an end elevational view thereof.

I claim:

The ornamental design for a display case, as shown.

ANTHONY A. ROSE.
